UNITED STATES PATENT OFFICE.

CHARLES H. SHATTUCK, OF MOSCOW, IDAHO.

PROCESS OF TREATING WOODS.

1,169,289.

Specification of Letters Patent. Patented Jan. 25, 1916.

No Drawing.

Application filed September 12, 1914. Serial No. 861,451.

To all whom it may concern:

Be it known that I, CHARLES H. SHATTUCK, a citizen of the United States, residing at Moscow, in the county of Latah and 5 State of Idaho, have invented a new and useful Process of Treating Woods, of which the following is a specification.

The present invention relates to improvements in a process for treating woods, one 10 object of the invention, being the provision of a process, by means of which the wood is colored and is made considerably lighter in weight, due to the removal of the gums, resins, etc., and by means of which the natural 15 luster of the wood remains and in which the grains are made more beautiful in the finished wood.

In carrying out the present process, wood of any character, either green or dried, is 20 placed in a retort capable of standing a pressure of 100 pounds to the square inch. Acid liquor derived from the destructive distillation of wood of any species and secured by any process, is then introduced 25 into the retort, and heat is then applied to a sufficient degree and at a pressure of a sufficient amount for the proper length of time to give the desired shade or color to the wood. The time varies with the species 30 used, and with the size of the sticks or planks, being approximately from two to forty-eight hours. It has been found in practice, that boards one inch thick will require from six to ten hours to produce the 35 desired effect. The wood is then removed and exposed to the air, when it is found to dry very rapidly and in a much shorter time than is necessary to dry green lumber, or if desired, the wood may be run through 40 any ordinary dry kiln. It has been found that with this process the wood is colored through and through, and is considerably lighter in weight due to the removal of the gums and resins which are displaced by the 45 lighter acid liquor, the water of which is later evaporated leaving the coloring matter of the acid liquor in every fiber of the wood. It has been found that the wood thus treated is more easily worked than untreated wood, 50 and will take a very high and beautiful polish, even without a filler. The wood thus treated has the natural luster when finished which is lacking where surface stains and dyes are used, and is therefore much more 55 beautiful as well as more permanent and

capable of standing rougher usage than when finished in fumed oak, or any of the mission or other dark stains which are only skin deep.

It has been found in practice that the acid liquor derived either from the destructive distillation of wood in retorts or by means of hoods and condensers, will effectively produce the desired coloring and seasoning and assists in reducing the weight 60 of the wood, it having been found that the described procedure may be carried on with a simple apparatus, embodying merely a retort as before stated that may be sealed to withstand approximately 100 pounds pressure to the square inch. It is also possible 70 to heat the retort exteriorly and force there-in air or steam to produce the desired pressure. It is therefore essential only that the lumber be treated with the acid liquor after 75 having been placed in the retort, and after such retort is sealed, with the liquid thus supplied, that the wood be subjected to heat and pressure. This it has been found causes the proper dissolving or extracting 80 of the gums, resins and other natural oils so that when the lumber is subjected to the atmospheric air, or in a dry kiln, the water from the acid liquor will evaporate and thus leave the wood permanently dyed or stained, 85 the grain being brought out in most beautiful effects.

It is apparent that any chemical composition that will be identical with and which may be made by other processes than is 90 usually employed in obtaining the herein specified acid liquor, can be used in the present process and that therefore where the words "acid liquors derived from the destructive distillation of wood" occurs, any 95 such chemical composition is covered thereby.

What is claimed is:—

1. The herein described process of lightening and coloring wood which consists in heating the wood under pressure and while 100 submerged in an acid liquor produced by the destructive distillation of wood.

2. The herein described method of lightening and coloring wood, which consists in placing the wood in a retort with acid liquor 105 derived from the destructive distillation of wood, and subjecting the contents of the retort to heat and pressure.

3. The herein described method of lightening and coloring wood, which consists in 110

placing the wood in a retort with acid liquor derived from the destructive distillation of wood; and subjecting the contents of the retort to heat and pressure to give the wood, 5 a color of one shade and then gradually increasing the heat and pressure to darken the color of the wood.

In testimony that I claim the foregoing as my own, I have hereto affixed my signature in the presence of two witnesses.

CHARLES H. SHATTUCK.
